FIG-1

FIG-2

FIG-3

FIG-5

FIG-4

FIG-6

FIG-7

FIG. 1 is a perspective view of an ink roller showing my new design;

FIG. 2 is a perspective view of the ink roller shown in FIG. 1 but looking at the opposite end thereof;

FIG. 3 is an elevational view of the ink roller;

FIG. 4 is an end elevational view looking toward the right in FIG. 3;

FIG. 5 is a top plan view of the ink roller as viewed in FIG. 3;

FIG. 6 is an end elevational view looking toward the left in FIG. 5; and

FIG. 7 is a bottom plan view of the ink roller as viewed in FIG. 3.

The characteristic feature of my design resides in the appearance of the end portion of the ink roller shown, for example, in elevation in FIG. 4.

I claim:

The ornamental design of an ink roller, substantially as shown.
